UNITED STATES PATENT OFFICE.

JOHN BADER, OF HAMPTON, VIRGINIA.

EXTENSION TABLE.

Application filed July 29, 1925. Serial No. 46,873.

This invention relates to that type of tables which includes a plurality of leaves which may be manipulated to form, at will, a large table surface or which may be disposed of so as to reduce the effective table surface to a normal minimum.

At the very outset, it may be stated that extension tables are generally well known and that many structural embodiments have 10 been heretofore used or proposed.

It is an object of this invention to provide an extension table which with a relatively small number of parts affords a large change as to size.

15 Another object is to provide a table of the character described that permits several stages of extension without the necessity of auxiliary legs.

Another object is to provide an extension 20 table permitting several extensions in which all the parts are so related that the table, whether extended or contracted, is as solid and firm as an ordinary table having no movable parts.

25 Other objects will clearly appear from the description in connection with the accompanying drawings.

The invention is not to be found so much in radically new parts as rather in the 30 specific correlation of various boards or leaves and means for bringing them into and out of definite positions, as will be more particularly pointed out in the claims.

In the drawings,

35 Fig. 1 is a perspective view showing the table in normal or unextended position;

Fig. 2 is a side elevation of the table in a partly extended condition, the legs being broken away;

40 Fig. 3 is a bottom plan view of the table in the condition of extension shown in Fig. 2;

Fig. 4 is a section on line 4—4, Fig. 3;

Fig. 5 is a side elevation of the table in 45 a different extended condition;

Fig. 6 is a bottom plan view thereof;

Fig. 7 is a sectional view on line 7—7, Fig. 6; and

50 Figs. 8, 9 and 10 are transverse sections on lines 8—8, 9—9 and 10—10, Fig. 7.

Having reference to Fig. 1, the table according to the invention has four legs 10^a

and 10^b, a top board or leaf 11 defining the exposed table surface in contracted condition; and two sets of leaves 12^a and 12^b, as 55 one group and 13^a and 13^b as a second group. As clearly appears, these two groups of leaves are symmetrically disposed relatively to each other and to the board 11 and co-operate with the latter to define a single 60 unitary construction of solid design and ruggedness. All the leaves constitute essential parts in the make-up of the table from the standpoint of construction as well as from the standpoint of ornamental value. 65

It may be stated here that each pair of legs can take part in one extension movement, independently of the other pair. There may be four separate and distinct 70 stages of extension, two on each side of the transverse center line of the table.

Figs. 2, 3 and 4 represent the table as the result of one step of extension at each side of the transverse center line; while Figs. 5, 6 and 7 represent it as the result of two steps 75 of extension on the same side.

The principal structural parts acting as supports are two groups of rigidly interconnected elements. One group comprises the legs 10^a, one end piece 14^a, similar side pieces 80 14^b, a cross piece 15 interconnecting the same and two slide guide members 16. The second group comprises the legs 10^b, an end piece 17^a, similar side pieces 17^b, a cross piece 19 interconnecting the same and two slide 85 guide members 20.

The two groups of elements just described are interconnected for sliding movement 90 relatively to each other by means of a pair of slide guide members 21. The members 21 have undercut grooves co-operating with corresponding tongues 22 on the guide members 16 and 18, respectively. Thus, the two groups of elements may be moved relatively to each other in the direction of the length 95 of the table and this movement is primarily instrumental in effecting one or two stages of extension, according to whether only one of the groups is moved or both groups are simultaneously drawn away from each other. 100 The slide guide members 16 and 20 and the slide guide members 21 are relatively heavy and of well seasoned stock and the tongues are of relatively large cross-section so that

the construction described, even in extended condition, represents a solid and rigid framework. The extended contact between the members 21, on the one side, and the members 16 and 20, on the other side avoids play and undesirable wobbling.

At the free ends of the members 16 and 20 are provided stops 23 co-operating with similar stops 24 adjacent the center of the members 21 to limit the extension movement.

The opposite side pieces 14^b and 17^b are normally kept in alignment by means of pins 25 on one piece fitting into corresponding bores in the opposing piece.

15 The guide members 21 are rigidly connected to a cross piece 27 which is interconnected with the main table board 11 so as to allow the latter to move away from it in vertical direction but prevent relative 20 movement laterally and lengthwise of the table. To this end the board 11 is provided with projections 28 movable into and out of corresponding recesses or apertures in the cross piece 27, as shown in Fig. 9. The relative movement in vertical direction is restrained by a spring 30 bearing against the underside of the cross piece 27 and supported by a stud 31 extending from the under side of the board 11 through a hole 30 in the cross piece 27, as clearly shown in Fig. 9. As a matter of expedience, I do not provide the projections 28 and the stud 31 directly on the board 11, but on a separate strip 32 which is secured to the board 11. The 35 projections are preferably slightly tapering so as to avoid binding. The strip 32 preferably terminates inwardly of the lateral edges of the board 11 and the cross piece 27 is made correspondingly thicker at its ends 40 so that the strip 32 normally rests in a saddle-like depression of the cross piece as clearly shown in Figs. 9 and 10. However, this feature is of minor importance.

The leaves 12^a and 12^b are connected with 45 the guide members 16 and 20, respectively, so as to move with the latter. The connection, however, is such that the leaves 12^a and 12^b may be moved relatively to the guide members. This connection, which is shown 50 in Fig. 7, includes a cam slot 33 on each of the guide members 16 and a cam slot 34 on each of the guide members 20. From the thickened end of the leaves 12^a and 12^b depend lugs 35 and 36, respectively, each of 55 which carries a journal 37 for co-operation with the cam slots.

The leaves 13^a and 13^b carry on their lower surfaces joist-like supports 40, the width of which increases from their outer ends just 60 inside the outer edges of the leaves, to their inner ends which are rounded and cut away to define recesses 40^a. The lower edges of the supports 40 are thus inclined, while the upper edges are horizontal. The cross pieces 65 14^a and 17^a have slots 41, the bottoms of

which are correspondingly inclined to form slideways for the supports 40, as indicated in Fig. 7. On the under side of the supports are provided stops 42 for limiting the extension movement.

The leaves 12^a and 12^b are provided at their inner thickened edges with projections 43, preferably of metal. These projections extend toward the transverse center line of the table and their upper surfaces are disposed below the upper surface of the leaves 12^a and 12^b, so that when the latter are extended, the main board 11 rests thereon, as indicated in Figs. 2, 3 and 4. The leaves 12^a and 12^b also carry at their inner edges 80 at the bottom of the thickened portion thereof of lugs 44 for supporting the inner edge of the leaves 13^a and 13^b, when the latter are in unextended position below the leaves 12^a and 12^b.

85 The operation is as follows:

When it is intended to effect the first extension at both ends, it is necessary to first take a hold on the end pieces 14^a and 17^a or any other part of the structure with which 90 the legs are connected and pull in opposite directions until the stops 23 and 24 coming into contact with each other prevent further movement. Then the two pairs of leaves 12^a and 13^a, on the one side, and 12^b and 13^b, 95 on the other side, are pulled as units. Thereby by the pins 37 are forced to ride up the inclined portions of the cam slots 33 and 34 and then along the horizontal portion of the cam slot. When the movement of the legs 100 has reached its limit, the leaves 12^a and 13^a or 12^b and 13^b as a unit are still below the main board 11 and a short distance inwardly of the outer edge thereof. Movement of the leaves 12^a and 12^b relatively to the guide 105 members 16 and 20 forces the leaves 12^a and 12^b upwardly. While the inner end of the upper leaf 12^a or 12^b is raised by the cam slot connection, the outer end is correspondingly raised by the end surface of the supports 40 which defines in fact a cam surface 40^b cooperating with the inclined bottoms of the slots 41, as clearly shown in Fig. 7 and Fig. 4. When the pins 37 have reached the upper end of the inclined portion of the cam slot, the leaves 12^a and 12^b have been lifted a distance equal to the thickness of the leaves and when the inner edges of the leaves have cleared the outer edges of the main board 11, the latter which was forced upwardly 110 against the tension of spring 30 by the upward movement of the leaves 12^a and 12^b, snaps back and comes to rest upon the projections 43, so that the upper surfaces of the board 11 and of the leaves 12^a and 12^b are 115 in the same plane, as indicated in Fig. 2. In this position the leaves 13^a and 13^b are confined below the leaves 12^a and 12^b and, but for the lines of separation, appear as single elements. The inner ends of the 120 125 130

leaves 13^a and 13^b rest on the lugs 44, as previously explained, and the inner ends of the leaves 12^a and 12^b firmly rest by means of the pins 37 in the horizontal portions of the cam slots 33 and 34. The outer ends of the leaves 12^a and 12^b rest upon the leaves 13^a and 13^b which in turn are firmly supported through the joist-like supports 40 upon the end pieces 14^a and 17^a respectively. 5 The inclination of the lower edges of the supports 40 is so chosen that in their position at the end of the first extension stage the outer ends of the leaves 12^a, 13^a and 12^b, 13^b, have been raised the same distance as the inner ends thereof have been raised by means of the cam slots 33 and 34. Thus, 15 the leaves 11, 12^a and 12^b define a single top surface and at the same time all parts are firmly supported, the center portion being supported, as previously pointed out, upon the members 21 which together with the members 16 and 20 form in effect a single rigid supporting structure. The outer edges of the main board 11, since they rest upon 20 the projections 43, which are a part of the leaves 12^a and 12^b, are of course as solidly supported as the leaves 12^a and 12^b. The depending lugs 35 and 36 are of metal and of such strength as to safely support the 25 load imposed upon them. The spring 30 exerts pressure upon the main board 11, which in turn bears through projections 43 upon the leaves 12^a and 12^b.

The table, after the first bilateral extension, is in effect just as solid a table as before the extension. The only apparent difference is the different spacing of the legs.

While for the sake of completeness, the simultaneous extension at both ends has been particularly described, one end alone may be extended, while the other end may be left in the original condition. The only apparent difference, again, is the different spacing of the legs.

To further extend the table at one or both ends, it is merely necessary to pull either one or both of the leaves 13^a and 13^b until they are, or either one of them is, in abutting relation to the leaves 12^a and 12^b or either one of them. The leaves 13^a and 13^b can be moved until the stops 42 strike against the end pieces 14^a and 17^a or rather against a metal stop plate thereon. When this position is reached the inner ends of the leaves have just cleared the outer ends of the leaves 12^a and 12^b, which during the movement have been raised at their outer ends in proportion to the inclination of the supports 40 and snap back and come to rest upon the supports 40. The inner edges of the leaves 13^a and 13^b are thus in absolute alignment with the outer edges of the leaves 12^a and 12^b and the outer ends of the leaves 13^a and 13^b have been raised exactly to the level at which the leaves 13^a, 13^b are in the

same plane as the leaves 12^a, 12^b and the main board 11.

The outer ends of the leaves are now supported by the supports 40 just the same as before, with the difference, however, that the leaves 13^a and 13^b are disposed entirely outside the outlines of the main supporting frame defined by the legs and associated supporting elements. The problem of static strength and rigidity of construction, however, is taken care of by means of the engagement of the inner ends of the supports 40 with the thickened portions of the leaves 12^a and 12^b. The recessed portions of the supports 40 bear upwardly against the thickened portions of the leaves 12^a and 12^b. Since these portions are firmly locked against vertical movement in either direction because of the engagement of the pins 37 in the horizontal portions of the cam slots 33 and 34, the rear ends of the supports are securely fixed. The supports, thus being securely supported at their ends and intermediate their ends upon the end pieces 14^a and 17^a, afford a rigid and strong support for the leaves 13^a and 13^b. The recesses 40^a are provided to allow the upper edge of the supports 40 to assume a true horizontal position. The leaves 12^a and 12^b, due to the co-operation of the pins 37 and the cam slot, have a sufficient pivotal movement at their inner ends to yield to the upward motion caused by the rise of the leaves 13^a and 13^b incident to their outward movement.

In the above, I have made reference to thickened ends of the leaves 12^a and 12^b. In practice I secure to the under side of the leaves 12^a and 12^b a separate strip of strong material which may be metal, if desired. This would be of particular advantage as the projections 43 and 44 may be formed as integral parts thereof. There is considerable latitude in this respect.

In the foregoing I have described the normal operation of obtaining separately or simultaneously four different extensions from a minimum to a maximum. It should be noted, however, that the leaves 13^a and 13^b may be separately drawn out while the other parts of the table remain as shown in Fig. 1. However, in that case, the upper surfaces of the leaves 13^a and 13^b are not flush with the surface of the main board 11. For many purposes this mode of extension has great advantages.

I claim:

1. In an extension table, the combination of a main table board defining the normal table surface, a supporting frame divided in two sections substantially along the transverse center line thereof, means for slidably interconnecting the two sections including a pair of slide guides forming part of one section, a pair of slide guides forming part

90

95

100

105

115

120

of the other section, one slide guide on each section being in sliding engagement with one slide guide on the other section, resilient means connecting the main table board to the supporting frame independently of the relative sliding movement of the two sections, a pair of extension leaves normally disposed in superposed relation between the supporting frame and the main table board on one side of the transverse center line thereof, the upper one of said leaves being connected at its inner edge to the pair of slide guides forming part of the supporting frame section, and means permitting limited movement of the said upper leaf in vertical direction away from the frame.

2. An extension table according to claim 1, wherein the said upper leaf is connected to the pair of slide guides forming part of the supporting frame section on which the leaves are supported, the connection including pins on the leaf and cam slots on the slide guides, the cam slots rising from a lower level outwardly toward the end of the table and terminating in horizontal portions.

3. In an extension table the combination of a main table board defining the normal table surface, a supporting frame divided in two sections substantially along the transverse center line thereof, means for slidably interconnecting the two sections, including a pair of slide guides on each section, a pair of extension leaves normally in superposed relation between the supporting frame and the main table board on one side of the transverse center line thereof, the upper one of said leaves having adjacent its inner edge a depending portion forming an abutment for the lower leaf and a connection between the upper leaf adjacent its inner end and the pair of slide guides on the section on which the leaves are supported, said connection permitting vertical movement of the upper leaf relatively to the supporting frame.

4. An extension table according to claim 3 including a pair of joist-like supports secured to the under side of the lower leaf and extending a distance inwardly of the inner edge thereof so that when the lower leaf is extended relatively to the upper leaf and in abutting relation therewith, the inner ends of the joist-like supports bear upwardly against the depending portion of the upper leaf, the joist-like supports being in sliding engagement with the supporting frame.

5. An extension table according to claim 3 including a pair of joist-like supports secured to the under side of the lower leaf and extending a distance inwardly of the inner edge thereof so that when the lower leaf is extended relatively to the upper leaf and in abutting relation therewith, the inner ends of the joist-like supports bear up-

wardly against the depending portion of the upper leaf, the joist-like supports having inclined lower edges rising from their inner ends toward their outer ends and being in sliding engagement with the supporting frame.

6. An extension table according to claim 3 including a pair of joist-like supports secured to the under side of the lower leaf and extending a distance inwardly of the inner edge thereof so that when the lower leaf is extended relatively to the upper leaf and in abutting relation therewith, the inner ends of the joist-like supports bear upwardly against the depending portion of the upper leaf, the joist-like supports having inclined lower edges rising from their inner ends toward their outer ends and being in sliding engagement with the supporting frame, and the lower edges being partly cut away at their inner ends to define seats bearing against the said depending portion of the upper leaf.

7. In an extension table, the combination of a supporting frame including the legs, divided in two sections substantially along the transverse center line, means for slidably interconnecting the two sections, including a pair of slide guides on each section and a separate pair of slide guide members interposed between and in sliding contact with one slide guide on each section, respectively, a main table portion resiliently connected with the separate pair of slide guide members to permit relative vertical movement, two pairs of extension leaves disposed in superposed relation between the supporting frame and the main table leaf on opposite sides of the transverse center line thereof, the upper one of each pair of leaves being connected at its inner end to one pair of slide guides and having a depending portion forming an abutment for the lower leaf, and joist-like supports secured to the under side of each lower leaf, said joist-like supports being of such length that the inner ends thereof bear upwardly against the said depending portions when the lower leaves are extended and in abutting relation to the upper leaves, the connection between the upper leaves and the slide guides, permitting vertical movement of the former relatively to the latter.

8. An extension table according to claim 7, including stops on the slide guides, the slide guide members and the joist-like supports for limiting the extension movements.

9. In an extension table, the combination of a main table board defining the normal table surface, a supporting frame divided in two sections substantially along the transverse center line thereof, means for slidably interconnecting the two sections, a pair of extension leaves normally disposed in superposed relation between the supporting

frame and the main table board on one side of the transverse center line thereof, the upper one of said leaves being connected to one section of the supporting frame and movable therewith and the lower one of said leaves being freely movably relatively to the supporting frame and the upper leaf, and

joist-like elements extending from the inner edge of the lower leaf, constructed and arranged to upwardly bear against the upper leaf when the lower leaf is extended and in abutting relation to the upper leaf. ¹⁰

In testimony whereof, I affix my signature.

JOHN BÄDER.
